VENDING MACHINE FOR ROLL MATERIAL

Frank S. Warner, Lincoln, Nebr.

Application April 6, 1931. Serial No. 528,003

1 Claim. (Cl. 242—55.3)

My invention relates to vending machines for roll material, the machine being designed initially and primarily for vending screen wire.

One of the objects of the invention is the provision of a support for any number of rolls or wire and of any desired lengths.

Another object of the invention is the provision of a support which will protect the rolls of wire from being bent or jammed or from being injured in any other way.

Another of the objects is the provision of a support which will maintain a plurality of rolls of wire in almost instant readiness to be measured and cut.

It is also my object to so design the support that no handling of the wire roll is necessary after the roll has been once installed so that there will be no necessity of removing the roll from the support until the entire roll is consumed.

It is my object also to not only make the support serve as a perfect protector of the wire cloth but to also greatly reduce the time and labor necessary for vending the material.

Another object of the invention is the provision of a support which maintains the wire roll at its normal diameter so that it cannot expand while on the support.

Having in view these objects and others which will be pointed out in the following description, I will now refer to the drawing, in which

Figure 1 is a view in perspective of my screen wire support.

Figure 2 is a cross sectional view through the reel and showing also the rounded top edge of the frame over which the wire is drawn.

The reel includes two discs 10 which are united in spaced apart and parallel relation by means of the outwardly concave troughs 11. While these may be made of any desired material, my preference is for steel discs and for sheet metal troughs of the kind used on the edges of roofs. The troughs 11 may be in any desired number from three up, the number depending on the maximum number of rolls of screen wire to be carried by the support.

The rolls of screen wire are indicated by the numeral 12. These rolls are seated in the troughs 11 as shown in Figure 2. In order to prevent the displacement of the rolls 12 from the troughs 11, I provide rods 13 in the form of bolts passing through both discs 10. These rods 13 function as axes for the rolls 12 which surround them. The rods 13 also serve to brace and strengthen the reel. The reel is also provided with a central

shaft 14 which passes through both discs 10 and which is securely connected with the discs 10 so that the discs and the shaft rotate as a unit. One end of the shaft is provided with a crank handle 15 as shown in Figure 1.

The support for the reel is in the form of a simple open frame having front corner posts 16 and rear corner posts 17. These corner posts are connected by means of transverse braces as shown in Figure 1 although the arrangement of the braces may be altered at will. In my preferred construction I arrange the transverse braces in the form of open shelves for supporting the rolls of screen wire which are kept in stock and which are thus readily available for insertion in the reel. The frame is provided with a pair of bearing blocks 18 for the shaft 14. A pin 19 is slidable through one of the bearing blocks 18 to cooperate with one of a plurality of concentric apertures 20 in one of the discs 10 for locking the reel against rotation in any desired operative position.

The upper ends of the posts 16 are connected by means of a half round 21, this being parallel to the axis of rotation of the reel. The scale 22 also connects the front corner posts 16 and it is calibrated to indicate the width of the wire in the roll, thus furnishing a convenient device for indicating the desired roll when the reel is turned. A vertical scale 23 is secured to one of the two corner posts 16, preferably the one at the right, and this enables the operator to measure off the desired length of screen wire.

In use the rolls of screen wire are secured to the reel by passing the rods 13 through their middle portions and then fastening the rods to the discs 10 by means of nuts. When the customer desires screen wire of a specific length and width, the crank handle 15 is turned until the scale 22 indicates that the roll of the desired width is in position. The pin 19 is then pressed in to latch the reel against further rotation. The free end of the wire on the roll is then grasped in the hands and is withdrawn over the top rounded edge of the half round 21 and the strip is measured against the scale 23. The measured length of wire may then be cut off by means of tin snips or other suitable cutting apparatus, the frame being provided with an elongated transverse opening at 24 for the easy manipulation of the shears. This opening 24 also cooperates with the scale 23 in insuring that the desired length of roll material be measured and cut off with reasonable accuracy. Another important function of the opening 24 is that the

roll material may be cut at a right angle to the edges of the material. The scale 23 is horizontal while the corner post 16 is vertical, the two being thus perpendicular to each other. The importance of this function resides in the fact that the roll material does not have to be trimmed to fit it into place and that no waste is involved when the material is properly cut from the roll. In order to facilitate the cutting on the proper line, 10 I provide a clip 25 which is spring pressed against the material during cutting and which may be thrown back out of the way when the material is being unwound from the roll. The operator merely throws the clip into operative position and 15 then pulls the material against the left-hand corner post 16 with his left hand while he severs the material with a pair of shears with the transverse opening 24 as a guide.

The rolls are held in place in the troughs 11 by means of the rods 13 which serve as axes for the rolls. The troughs 11 ordinarily hold the material against unwinding. When the roll becomes small in diameter, however, it is very apt to unwind suddenly and to fall out. To prevent 25 such unwinding and to keep the roll in more compact condition, I secure resilient presser members 26 to the troughs 11 in a manner such that they will bear against the material in the roll. These presser members 26 may be in any of 30 several different forms but those which I have illustrated consist of spring steel rigidly secured to the troughs and having rounded free ends which readily permit the turning of the roll in either direction but which prevent any unwinding 35 of the roll.

While I have described my invention as particularly applicable to the dispensing of screen wire or wire cloth of all kinds, it is obvious that with possibly slight changes in dimensions the

support may be used for vending wire fencing, poultry netting, oilcloth, building material, linoleum, dry goods and other material which is available in roll form. It may also be used in shipping departments and similar places as a support for wrapping paper. Although I have confined myself in the description to the one specific use with screen wire, I wish it to be understood that I reserve to myself the right to employ the support to any and all uses for which the support is adapted.

Having thus described my invention in such full, clear, and exact terms that its construction and operation will be readily understood by others skilled in the art to which it pertains, what I claim as new and desire to secure by Letters Patent of the United States is:

In a vending machine for roll material, a support having front, rear and side members in rectangular relation and having supporting legs 95 at the corners thereof, a shaft journaled in said side members, a reel secured to said shaft between said side members, said reel including a pair of discs with a plurality of channel members connecting said discs, rods releasably secured between said discs and positioned in the arcuate centers of said channel members, said rods being adapted to support rolls of roll material, said front member of said support having a rounded upper edge and a transverse slot 105 therebeneath, means for latching said reel against rotation with the supporting rod of any desired roll positioned below the level of said front member of said support, and fixed transverse and vertical scales at the front of said 110 support for indicating the width and the length of the piece of roll material to be cut off.
